Letters Patent

The Schedule referred to in these Letters Patent and making part of the same containing a description of the words of the said Lewis H. May, himself of his improvements to a Patent now branching machine for straighting hair in combing down in the ears.

to all to whom these presents shall come, I, Dr. J. Brown, M.D.,
Living at Minard, in the County of Williamson and State of
West Virginia, have invented a novel and useful improvement on the
construction of oil to oil threshing machinery, for threshing wheat, Rye, and
other small grain, to be used in the car for the purpose of preparing it to
feed cattle, and that the following is a full and exact description thereof.
Specification. The breaker of oil to oil cylinders is one piece, with one
end cast to the cylinder, which has a square hole in its center for to
insert a iron shaft. The iron cylinder is cast hollow with both surfaces
in regular rows on its outside a narrow side and in a straight line and
of the cylinder being open. It cast an iron head with a square hole in its
center, but the iron shaft before mentioned to pass through. The head is
fitted into the open end of the cylinder and fastened with screws and nuts,
the cylinder when complete is hung to the back of the aforesaid iron
shaft (or threshing). The breaker consists of cast iron which is
cast in sections with 5, 6, 7, 8 or 9 teeth on each section, and the
teeth being of length and breadth as to form a straight line with each
row (or surface) the cylinder used in former Brown's threshing machine
is cast in round one and a half inches thick, with the teeth on the edge
and hung on an iron bar passing through the middle. The great object
to this mode of construction is first its weight which requires no horses
hence to keep it in motion. This my invention obviates by all means
heavy and the weight being principally on the outside of the circle of
the cylinder. The cylinder being cast around the teeth supports

cannot be made of equal length or height in a time which permits the men
to swing let down to the concave for the thickness of a small granite. This may in
vention obviates by the two supports being all in line on each row so that
it can be let down or raised at the pleasure of the persons using it. 3rd
The concave being cast in sections instead of each board being cast separately
facilitates the building of the machine by saving labour and tends
to its more general use. This frailty being all of a length and in a time
11th My invention having the cylinders cast in one piece is much
cheaper ^{owing} to the weight of casting and less labour in its construction.

Danielle, Columbia County, Pennsylvania, November 20th 1835.
